United States Patent Office

Des. 221,857
Patented Sept. 14, 1971

221,857

BREATH TESTING MACHINE CABINET

Herbert C. Schulze, Carlsbad, Calif. 92008; Sam Priestly, Carlsbad, Calif. (P.O. Box 1069, Oceanside, Calif. 92054); and Marthe-Ann Klimo, P.O. Box 105, Encinitas, Calif. 92024

Filed May 13, 1970, Ser. No. 22,950

Term of patent 3½ years

U.S. Cl. D26—1   Int. Cl. D21—04

FIG. 1 is a perspective view showing a breath testing machine cabinet embodying our new design;

FIG. 2 is a front elevational view of said machine;

FIG. 3 is a side elevational view of said machine with the side opposite that shown having the same appearance; and

FIG. 4 is a top view of said machine.

We claim:

The ornamental design for a breath testing machine cabinet, substantially as shown and described.
